UNITED STATES PATENT OFFICE.

FREDERICK MONDELET GAUDET, OF QUEBEC, CANADA.

TARGET FOR MINIATURE RANGES.

SPECIFICATION forming part of Letters Patent No. 738,790, dated September 15, 1903.

Application filed February 8, 1902. Serial No. 93,180. (No model.)

To all whom it may concern:

Be it known that I, FREDERICK MONDELET GAUDET, a subject of the King of Great Britain, residing at Quebec, in the Province of Quebec, Canada, have invented a new and useful Target for Miniature Ranges, of which the following is a specification.

My invention relates to improvements in targets for miniature ranges; and the object 10 of my invention is to provide a target which shall allow of practice with small-arms or ordnance of any description being carried on in confined or limited places and without the expense entailed by using full-sized ammunition, and, further, to have the said miniature target of such size and arrangement that the skill required to place a shot in any division of the miniature target when using specially-prepared ammunition with a reduced 15 charge will be substantially equal to the skill required to accomplish the same results in any corresponding division of the full-sized target with full-sized ammunition, and, further, to provide means whereby the effect of 20 wind is obtained by an apparent deviation of the bullet from the center of the target and generally to reproduce in a miniature range the conditions and difficulties which obtain in a full-sized range; and it consists, essentially, of an aiming-target and a scoring-target 25 the vertical distance between whose centers is equal to the distance between the line of sight and the trajectory at their intersection with the plane of the target, the dimensions of the scoring-target being such that 30 the probable number or percentage of hits contained in any figure or division of the target when using the miniature ammunition will be exactly equal to the probable number 35 or percentage of hits contained in any figure or division of the full-sized target when using full-sized ammunition, the various parts of 40 the device being constructed and arranged in detail, as hereinafter more particularly described.

Figure 1 is a view of my target for miniature ranges, indicating the relative positions of the aiming and scoring targets for use on a miniature range when practicing point- 45 blank shooting. Fig. 2 is a view of my target for miniature ranges, indicating the relative positions of the aiming and scoring tar-

gets as used when practicing long-range shooting. Fig. 3 is a view of my target for miniature ranges, indicating the relative positions 55 of the aiming and scoring targets as used to represent the wind effect on a long range. Fig. 4 is a diagrammatic view of a miniature range in which a target is being used for point-blank practice. Fig. 5 is a diagrammatic view of a miniature range in which a target is being used for long-range practice.

In the drawings like letters of reference indicate corresponding parts in each figure.

It may be here mentioned that it is my intention to use cartridges of the ordinary size in connection with my target; but the said cartridges will have a reduced charge of explosive, so that the rifle may be used without a miniature barrel, and in this way the conditions on the full-sized range may be more nearly represented on the miniature range than by the use of miniature barrels, which have been used heretofore. It will be understood, however, that there is nothing to prevent the use of rifles with miniature barrels with these targets if it is desirable to do so.

A is the aiming-target, comprising the bull's-eye and the outer rings or zones a' a'' , &c.

B is the scoring-target, comprising the bull's-eye b' b'' , &c.

The aiming-target A is indicated in heavy lines, so as to be plainly visible to the firer. The scoring-target B is preferably made in light or dotted lines and is visible only to the 85 marker in order that the firer will not confuse it with the aiming-target. The vertical distance between the centers of the aiming-target and the scoring-target, which is indicated by the letter C in the drawings, is equal 90 to the vertical distance between the trajectory and the line of sight at their intersection with the plane of the target for any given elevation of the piece, and it is determined experimentally.

When the firer is instructed to prepare for practice at a point-blank range, the rear sight of the piece will be in the ordinary lowered position, as in Fig. 4. The line of sight E will point directly at the center of the bull's-eye of the aiming-target; but owing to the fact that a reduced charge is used in the cartridge the trajectory F will drop considerably and will intersect with the plane of the tar-

get below the center of the aiming-target. It is at this point of intersection that the center of the scoring-target will be placed, so that in a perfect shot although the line of sight points directly at the center of the aiming-target A the bullet will strike the center of the scoring-target B.

In Fig. 5 the conditions are shown which exist when the firer is instructed to adjust his sights for a long range. The rear sight G is accordingly raised, as shown, and the rifle will point upwardly at an angle which will be greater or less, according to the range at which the firer is supposed to be practicing. The line of sight F' in this case will point directly at the center of the aiming-target A; but the trajectory will rise above the line of sight and will strike the target at a point which may be considerably above the center of the aiming-target, the distance between this point and the center of the aiming-target depending on the elevation given to the piece or, in other words, on the range represented by the miniature range.

25 The dimensions of the aiming-target are determined in proportion to the dimensions of the full-sized target, varying inversely as the range to be represented, so that the firer will aim at a target having the same appearance as the full-sized target would have at the full-sized range.

The method of calculating the dimensions of the scoring-target is as follows: The "accuracy" or mean absolute deviation of the 35 full-sized ammunition at the full-sized range is calculated by well-known means. The mean absolute deviation or accuracy of the miniature ammunition at the miniature range is also calculated. The dimensions of the 40 full-sized target to be represented are known, and the dimensions of the scoring-target will bear the same relation to the accuracy of the miniature ammunition at the miniature range as the dimensions of the full-sized target bear 45 to the accuracy of the full-sized ammunition at the full-sized range.

A further point of improvement in my target is shown in Fig. 3, in which the scoring-target is set slightly to one side of the aiming-target, the object of this being to give the firer practice in adjusting his sights to compensate for the wind causing a deflection of the projectile. In actual practice the marker will move the scoring-target, for example, 55 a distance D to the right and will indicate by a signal to the firer that the wind is coming from the right and that he must adjust his sights accordingly. The shooter can then fire one shot to discover the deflection for 60 which he must make an allowance, after which shot he can make what he considers the proper allowance for the deflection due to the wind.

It will now be seen that I have invented a 65 target for use on miniature ranges in which the skill required to place a certain number of shots within any division is substantially

the same as the skill required to place the same number of shots in a corresponding division of the full-sized target and in which 70 the effect of wind may be produced and in general a target which reproduces the conditions of a full-sized range in a limited space.

It will of course be understood that the target need not be circular in form, as shown, 75 but may take any other regular or irregular form—as, for example, the figure of a man—and, further, during exposure to firing both the aiming and scoring targets may be fixed or caused to move in any direction, either 80 continuously or intermittently, to represent a moving enemy or animal, as the case may be. Again, although I have described the method of absolutely determining the correct size for the scoring-target it will be understood that in practice it is not necessary to rigidly adhere to the dimensions determined by calculation so long as the spirit of the invention is not departed from.

I am aware that miniature targets have 90 been known in which an aiming-target is used having the appearance or visible size of a full-sized target in connection with a scoring-target consisting of a card or plate whose size bears no definite relation to the size of the 95 full-sized target as used on the range represented; but it will be seen that in such targets, although the aiming conditions may be practically the same as those of the full-sized target, still the chance of scoring is not the 100 same, as the dimensions of the scoring portion of the target do not bear any definite relation to or, in other words, are not calculated from the dimensions of the full-sized target and the relative accuracies of the miniature and full-sized ammunition. In my target, as above pointed out, the difficulties of 105 aiming and the chance of a shot coming in the bull's-eye when correctly aimed are exactly the same on the miniature as on the full-sized target at their respective ranges. It will also be understood that I may use an indicating-target in connection with my miniature target on which the marker will indicate to the firer the result of his shot; but I 110 do not claim this as my invention, as such a device has been commonly used in connection with ordinary targets.

What I claim as my invention is—

1. In a target for miniature ranges, the combination with an aiming-target, of a scoring-target, the dimensions of which bear the same relation to the accuracy of the miniature ammunition at the miniature range as the dimensions of the full-sized target bear to the 125 accuracy of the full-sized ammunition at the full-sized range to be represented, as and for the purpose specified.

2. In a target for miniature ranges, the combination with an aiming-target, of a scoring-target the dimensions of which bear the same relation to the accuracy of the miniature ammunition at the miniature range as the dimensions of the full-sized target bear to the 130

accuracy of the full-sized ammunition at the full-sized range to be represented, and the vertical distance between the centers of the aiming and the scoring targets being equal

5 to the vertical distance between the trajectory and the line of sight at their intersection with the plane of the miniature target, as and for the purpose specified.

3. In a target for miniature ranges, the combination with an aiming-target, whose dimensions are in proportion to the dimensions of the full-sized target, inversely, as the distance to be represented, of a scoring-target the dimensions of which bear the same relation to accuracy of the miniature ammunition at the miniature range as the dimensions of the full-sized target bear to the accuracy of the full-sized ammunition at the full-sized range to be represented, and the vertical dis-

10 tance between the centers of the aiming and the scoring targets being equal to the vertical distance between the trajectory and the line of sight at their intersection with the plane of the miniature target, as and for the pur-

15 pose specified.

4. In a target for miniature ranges, the com-

bination with an aiming-target whose dimensions are in proportion to the dimensions of the full-sized target, inversely, as the distance to be represented, of a scoring-target 30 the dimensions of which bear the same relation to the accuracy of the miniature ammunition at the miniature range as the dimensions of the full-sized target bear to the accuracy of the full-sized ammunition at the full-sized range to be represented, the vertical distance between the centers of the aiming and the scoring targets being equal to the vertical distance between the trajectory and the line of sight at their intersection with the plane 40 of the miniature target, and the center of said scoring-target lying in a separate vertical from the vertical containing the center of the aiming-target, as and for the purpose specified.

45 Signed at the city of Quebec, in the Province of Quebec, this 11th day of January, 1902.

FREDERICK MONDELET GAUDET.
